UNITED STATES PATENT OFFICE

EMIL H. BLATTNER, OF ROCHESTER, NEW YORK, ASSIGNOR TO THE SYMINGTON COMPANY, OF NEW YORK, N. Y., A CORPORATION OF NEW YORK

DRAFT GEAR

Application filed October 23, 1930. Serial No. 490,746.

This invention relates to railway draft rigging and cushioning mechanism for use therewith.

The principal object of my invention, generally considered, is to provide a preferably double-ended draft gear or cushioning mechanism with twin arranged springs, and adapted for series application to provide a greater buffering than draft energy-absorbing capacity, with a housing slotted for receiving a draft key or other connecting means.

Another object of my invention is to provide cushioning mechanism comprising a housing or casing with twin arranged pockets, each of which contains a series of ring springs presenting inclined friction surfaces in engagement with one another, and a closure member for each pocket telescoping therein for compressing said springs.

20 A further object of my invention is to provide cushioning mechanism enclosed in a double-ended housing having twin arranged pockets and a transverse web, disposed between said pockets, and providing the inner walls for the same, adapted to position associated ring spring cushioning means, the ends of said housing being normally closed by inwardly opening closure members telescoping therein, said members being provided with means for locking the same in place, with provision for limited relative movement thereof.

Other objects and advantages of the invention relating to the particular arrangement and construction of the various parts will become apparent as the description proceeds.

Referring to the drawing illustrating my invention, the scope whereof is defined by the appended claims:—

40 Figure 1 is a partial side elevation and partial longitudinal sectional view of one embodiment of my cushioning mechanism, an associated yoke and the stem of an associated coupler being shown diagrammatically.

45 Figure 2 is a partial end elevation and partial transverse section on the line 2—2 of Figure 1, looking in the direction of the arrows.

Figure 3 is a transverse sectional view on

the line 3—3 of Figure 1, looking in the direction of the arrows.

Referring to the drawing in detail, like parts being designated by like reference characters, there is shown a form of double-ended series friction draft gear 1 involving a housing or casing 2 having longitudinal walls 3 and transverse walls 4, defining twin arranged cushioning mechanism pockets 5 which, in the embodiment disclosed, are disposed one above the other, although it will be understood that my gear may be employed with the pockets arranged side by side, if desired. Each pocket 5 is preferably generally cylindrical and joined to the laterally adjacent pocket by having the cylindrical wall portions merge approximately tangent to one another, forming a longitudinally extending partition wall, as indicated by the reference character 6. On account of the transverse wall or walls 4 in the embodiment shown, each cylindrical pocket 5 is divided into two longitudinally spaced compartments, making a total of four spring-receiving compartments or pockets 5.

70 The longitudinal partition wall 6 is desirably provided with a longitudinal slot 7 which extends from one side of the housing 2 to the other, the twin arranged pockets 5 being preferably so positioned that the slot 7 is substantially tangent thereto, whereby said pockets open into said slot, as indicated at 8, economizing material and space and facilitating core removal. The slot 7 is preferably disposed midway between the ends of the housing 2, and the transverse walls 4 are preferably similarly disposed so that they extend from the mid portion of the slot 7. When connected with associated draft rigging, the slot 7 receives a draft key 9, the ends of which are received in registering slots 10 in the associated yoke 11, and are continued into slots 12 in the associated cheek plates and/or draft sills of the railway vehicle (not shown). The forward ends of the yoke arms are adapted for connection with an associated coupler 13 by means of a horizontal key 14, as will be understood.

75 A front follower 15 is desirably disposed between the butt or rearmost end of the cou-

pler 13, and the front of the cushioning mechanism 1, and a rear follower 16 is likewise disposed between the yoke 11 and the rear end of the cushioning mechanism 1, the rear face of the yoke 11 being adapted to abut the backstop 17, as will be understood.

The slotted portion of the housing is desirably extended beyond the sides of the longitudinal walls 3, as shown most clearly in Figure 2, by providing laterally extending flanges 18 surrounding the slot 7 and through which said slot continues to the sides of the gear. The ends of said flanges are preferably tied into the outer surfaces of the longitudinal webs 3 by means of transverse tapering webs or gussets 19. The outer surfaces of the longitudinal walls or webs 3 at the ends of the gear are preferably braced together by means of transverse webs or gussets 20, and the upper and lower surfaces of said webs 3 are desirably flat, as indicated at 21, whereby the housing, although composed of two generally cylindrical portions, is generally rectangular in outline.

Closing the outer open ends of the pockets 5 are four closure members or supplemental housings 22, said closure members having end walls 23 and side walls 24 telescoping with the longitudinal or side walls 3 of the housing 2, said walls, where they receive said closure member 22, being desirably cut out or made thinner, as indicated at 25, to receive the sides 24 of the closure members between the walls 3 and the springs, generally designated by the reference character 26. In order to interlock the closure members 22 with respect to the housing 2, said closure members preferably have lugs 27 struck out therefrom, and the walls of the housing are provided with grooves 28 receiving said lugs 27 and permitting inward movement thereof from normal position, as shown most clearly in Figure 1, without bending of said lugs, while providing shoulders 29 for limiting outward movement of the lugs and closure members 22, as will be understood.

Although a specific form of closure member retaining means has been disclosed, it will be understood that this is merely illustrative, as other retaining means may be used, if desired.

Disposed in each pocket 5 between the transverse wall 14 and a closure member 22 is a series of ring springs 26, said springs being desirably made of rolled spring steel and the rings being alternately placed in compression and tension when the gear is compressed. In the embodiment illustrated, the nest of ring springs is composed of individual rings 30 to 52, inclusive, the springs 30, 32, 34, 36, 38, 40, 42, 44, 46, 48, 50 and 52 being placed in compression when force is applied to the gear, and the other rings being under tension at that time. All of said rings have engaging inclined friction surfaces 53,

so that when the gear is compressed, the force applied is resisted not only by the resiliency of the springs, but also by the friction developed at the engaging friction surfaces. In order to provide a gear in which the initial resisting force is relatively small, some of the rings, for example, the tension rings 31, 33, 35, 37, 39 and 41, are desirably formed of smaller cross-sectional area and, therefore, weaker than some of the other springs, such as the remaining compression springs. For this same reason, one or more of the inner or compression rings are desirably split, as indicated at 54, to soften the resisting force of the gear at the beginning of the stroke. By having some of the inner tension rings stronger or thicker than the remaining outer tension rings, and having the pocket beyond the thicker tension rings enlarged, as indicated at 25, an annular space is provided to accommodate the side wall 24 of the associated closure member 22, and permit the necessary compressive movement thereof, as shown most clearly in Figure 1. The ring assembly is desirably packed during manufacture with wool waste soaked in graphite grease, or other suitable lubricant, thereby minimizing wear on the friction surfaces and resulting in long life.

The operation of my cushioning mechanism may be as follows, assuming the coupler stem 13 to be connected to a horizontal yoke 11, as by means of a key 14, and that the corresponding slots 12 in the cheek plates and/or draft sills (not shown) are extended rearwardly beyond the normal position of the slots 7, so that under the action of buffing forces, the housing is allowed to move rearwardly, while under the action of draft forces it is retained immovable, or substantially so, with respect to the associated sills. When draft forces are applied to the coupler 13, the yoke 11 is pulled forwardly, moving the rear follower 16 toward the housing and telescoping the rear closure members 22 into the housing 2, compressing the ring spring assemblies and utilizing only one half of the total capacity of the double end gear disclosed, permitting the coupler to travel only one half of the total permissible compression of the gear on account of said housing 2 being held stationary by the key 9.

Under the action of buffing forces, however, the coupler stem or butt 13 engages the front follower 15, pushing the closure members 22 into the corresponding end pockets in the housing, and at the same time, moving the housing rearwardly to cause it to telescope over the rear closure members 22 because of the rearward elongation of the slots 12, it being understood that the rear portion of the yoke or rear follower is associated with the backstop 17, or other limiting means, for effecting compression of the mechanism. It will, therefore, be seen that a full compres-

sion of the gear at both ends is permitted on buff, thereby providing for not only an increased buffing capacity but for a coupler travel equal to the sum of the travel permitted by the friction elements at each end of the gear.

Although for convenience and economy in manufacture the gear or cushioning mechanism is preferably made symmetrical so that the travel and capacity provided by each end is identical, yet this is not essential, as the capacities and travels of the two ends of the gear may be equal or different, as desired.

Although I have described a preferred manner of using my double end gear, it is to be understood that, if desired, it may be utilized so that the total capacity is used under both buff and draft, and it may also be employed so that the side walls or side portions of the longitudinal walls are disposed as top and bottom walls, that is, the gear may be used after being rotated through 90° about a longitudinal axis.

From the foregoing description, taken in connection with the accompanying drawing, it will be seen that I have devised an improved form of series draft gear or cushioning mechanism involving twin arranged nests of ring springs enclosed in a housing as a unitary cushioning device, and adapted to be used to provide differential shock-absorbing capacity under buff and draft. By providing a housing with a slotted central portion and outwardly opening end pockets receiving telescoping closure members, I can conveniently provide for the reception of four nests of ring springs centered by the generally cylindrical wall portions of the housing, space being economized by having the slot for the draft key extend between the twin arranged nests of springs and generally tangent to the spring receiving pockets. By having the closure members 22 formed of steel, resilient lug portions 27 may be struck out therefrom and serve as automatic locking means for the closure members, which may be assembled by pushing into place until the locking lugs 27 spring outwardly back of the shoulders 29 on the walls of the housing pockets.

Although I have illustrated a preferred embodiment of my invention, it will be understood that modifications may be made within the spirit and scope of the appended claims.

I claim:—

1. Cushioning mechanism comprising a housing with twin arranged pockets adapted to receive resilient means, a transverse web defining the inner ends of said pockets, said housing having a slot disposed between said pockets and adapted to receive a connecting draft key, a closure member for each pocket comprising an end wall and side walls normally telescoping in said pockets, said side walls having lugs struck out therefrom and

adapted to engage corresponding shoulders on the inner sides of said pockets for limiting outward movement of said closure members, the sides of said housing being grooved inwardly of said shoulders to receive said lugs and allow said closure members to slide inwardly of the housing without bending said lugs, and resilient means received in each pocket and held assembled by said closure members.

2. Cushioning mechanism comprising an integral housing member with pairs of twin arranged pockets separated by a longitudinal partition, a pair of said pockets opening forwardly and another pair opening rearwardly, said housing having a transverse web separating the forwardly and rearwardly opening pockets and disposed substantially midway between the ends of said housing, said partition being formed with a slot intersecting the wall and disposed substantially midway between the ends of said housing, a closure member for each pocket normally disposed in telescoping relation therewith, and a series of resilient rings received in each pocket and nesting with one another so that when force is applied to the mechanism said rings are alternately placed under compression and tension.

3. An integral housing adapted for cushioning mechanism and formed with pairs of twin-arranged pockets separated by a longitudinally extending partition wall, a pair of said pockets opening in one direction and another pair opening in the opposite direction, said partition wall being formed with a slot extending therethrough and disposed substantially midway between the ends of said housing, the inner ends of said pockets being defined by transverse walls extending from approximately the mid portions of the slotted part of said partition.

4. Cushioning mechanism comprising a housing with a pocket adapted to receive resilient means, a closure member for said pocket comprising end wall and side wall portions and normally telescoping in said pocket, said side walls portion having lugs struck out therefrom, and the sides of said housing being grooved to receive said lugs and allow said closure member to slide inwardly of the housing without distortion of said lugs, the outer ends of said grooves terminating in shoulders engaged by said lugs at the normal outer position of said closure member to hold it assembled with respect to said housing.

In testimony whereof I have affixed my signature.

EMIL H. BLATTNER.
